ELECTRIC COMBINATION LOCK SWITCH

Charles J. Streib, New Castle, Pa.

Application September 18, 1933, Serial No. 689,996

1 Claim. (Cl. 200—45)

This invention relates to electrical combination lock switches for controlling electrical circuits, and has for the primary object the provision of a device of the above stated character which will be simple in construction, positive in operation and capable of providing a large variety of combinations and wherein any one of the combinations may be readily changed to another combination.

10 With these and other objects in view this invention consists in certain novel features of construction, combination and arrangement of parts to be hereinafter more fully described and claimed.

15 For a complete understanding of my invention, reference is to be had to the following description and accompanying drawings, in which

Figure 1 is a top plan view illustrating an electrical combination lock switch constructed in accordance with my invention.

Figure 2 is a sectional view taken on the line 2—2 of Figure 1.

Figure 3 is a sectional view taken on the line 3—3 of Figure 2.

25 Figure 4 is a detail sectional view showing a connecting post employed between a series of cleats constituting part of the switch.

Figure 5 is a fragmentary sectional view showing one of the switch elements in circuit closing 30 position.

Figure 6 is a similar view showing breaking of the circuit by the switch element.

Figure 7 is a diagrammatical view illustrating the wiring diagram of the switch.

35 Referring in detail to the drawings, the numeral 1 indicates a switch supporting plate constructed of insulating material and arranged above the plate 1 is a guide plate 2 also constructed of insulated material. Arranged above the

40 plate 2 are plates 3 and 4 closely associated with each other and cooperating with the plate 2 in slidably supporting a series of plungers 5 each provided with a finger piece 6. The finger pieces 6 each are designated by a character, as shown

45 in Figure 1, so that the various plungers may be easily distinguished from each other. One of the plungers is centrally located with respect to the described plates while the other plungers are located circularly adjacent the periphery of the

50 plates. It is intended that the plates described be confined within a suitable casing, not shown, with the plate 4 exposed to view. The plates are connected by tie bolts 7 having spaced sleeves 8 thereon for retaining the various plates in proper relation to each other. The plungers 5 are

normally urged away from the plate 1 by springs 9.

A plurality of double acting switches 10 are supported on the switch plate 1 and each include bifurcated contacts 11, 12 and 13. Each contact 12 has pivoted thereto a switch lever 14 adapted to alternatingly engage the contacts 13 and 11 during its pivotal movement. The switch levers 14 are grouped radially upon the switch plate 1

with their inner ends terminating adjacent the center of the plate to be engaged by the centrally located plunger. Each contact is provided with a binding post 15. The centrally arranged plunger when moved against the action of its respective spring is adapted to simultaneously position all of the switch levers 14 in engagement with their respective contacts 11 and when in this position break the electrical circuit to which the switch is connected. In order to close the circuit

55 certain plungers of the circularly arranged group must be actuated so that certain of the switch levers 14 will be moved in engagement with their respective contacts 13. Therefore, it is necessary that a person know the combination in order to complete the circuit by this switch, as for instance, if an incorrect plunger is manipulated to cause pivotal movement of an improper switch lever to the combination, the circuit will remain

60 broken due to the fact that that particular switch lever moves out of engagement with its respective contacts 13. Therefore, it is necessary that a person know the combination in order to complete the circuit by this switch, as for instance, if an incorrect plunger is manipulated to cause pivotal movement of an improper switch lever to the combination, the circuit will remain

65 broken due to the fact that that particular switch lever moves out of engagement with its respective contacts 13. Therefore, it is necessary that a person know the combination in order to complete the circuit by this switch, as for instance, if an incorrect plunger is manipulated to cause pivotal movement of an improper switch lever to the combination, the circuit will remain

70 broken due to the fact that that particular switch lever moves out of engagement with its respective contacts 13. Therefore, it is necessary that a person know the combination in order to complete the circuit by this switch, as for instance, if an incorrect plunger is manipulated to cause pivotal movement of an improper switch lever to the combination, the circuit will remain

75 broken due to the fact that that particular switch lever moves out of engagement with its respective contacts 13. Therefore, it is necessary that a person know the combination in order to complete the circuit by this switch, as for instance, if an incorrect plunger is manipulated to cause pivotal movement of an improper switch lever to the combination, the circuit will remain

80 broken due to the fact that that particular switch lever moves out of engagement with its respective contacts 13. Therefore, it is necessary that a person know the combination in order to complete the circuit by this switch, as for instance, if an incorrect plunger is manipulated to cause pivotal movement of an improper switch lever to the combination, the circuit will remain

85 broken due to the fact that that particular switch lever moves out of engagement with its respective contacts 13. Therefore, it is necessary that a person know the combination in order to complete the circuit by this switch, as for instance, if an incorrect plunger is manipulated to cause pivotal movement of an improper switch lever to the combination, the circuit will remain

90 broken due to the fact that that particular switch lever moves out of engagement with its respective contacts 13. Therefore, it is necessary that a person know the combination in order to complete the circuit by this switch, as for instance, if an incorrect plunger is manipulated to cause pivotal movement of an improper switch lever to the combination, the circuit will remain

95 broken due to the fact that that particular switch lever moves out of engagement with its respective contacts 13. Therefore, it is necessary that a person know the combination in order to complete the circuit by this switch, as for instance, if an incorrect plunger is manipulated to cause pivotal movement of an improper switch lever to the combination, the circuit will remain

100 broken due to the fact that that particular switch lever moves out of engagement with its respective contacts 13. Therefore, it is necessary that a person know the combination in order to complete the circuit by this switch, as for instance, if an incorrect plunger is manipulated to cause pivotal movement of an improper switch lever to the combination, the circuit will remain

105 broken due to the fact that that particular switch lever moves out of engagement with its respective contacts 13. Therefore, it is necessary that a person know the combination in order to complete the circuit by this switch, as for instance, if an incorrect plunger is manipulated to cause pivotal movement of an improper switch lever to the combination, the circuit will remain

110 broken due to the fact that that particular switch lever moves out of engagement with its respective contacts 13. Therefore, it is necessary that a person know the combination in order to complete the circuit by this switch, as for instance, if an incorrect plunger is manipulated to cause pivotal movement of an improper switch lever to the combination, the circuit will remain

Having described the invention, I claim:

A switch comprising a supporting structure, a series of spring pressed plungers carried by the said structure, double acting switches mounted on the structure each arranged to be engaged by a plunger and each including three spaced contacts and a pivotal lever, means for connecting the switches in an electric circuit, means electrically connecting the contacts so that the

closing of the circuit by said switches must be through the operation of certain of said plungers while operation of the other plungers maintains the switches in position to break the circuit, said pivotal levers arranged radially upon the supporting structure, and a spring pressed plunger to engage the levers simultaneously for breaking the circuit. 80
